UNITED STATES PATENT OFFICE.

CORNELIUS G. HASTINGS, OF GLENDALE, CALIFORNIA.

REINFORCED BLOCKS AND INTERLOCKING MEANS THEREFOR.

1,381,119.

Specification of Letters Patent. Patented June 14, 1921.

Application filed June 24, 1918. Serial No. 241,515.

To all whom it may concern:

Be it known that I, CORNELIUS G. HASTINGS, a citizen of the United States, and a resident of the city of Glendale, in the county of Los Angeles and State of California, have invented certain new and useful Improvements in Reinforced Blocks and Interlocking Means Therefor; and I hereby declare that the following is a full, clear, and exact description of the same, reference being had to the accompanying drawings, and to the numerals of reference marked thereon, which form a part of this specification.

15 This invention has reference more particularly to a block for building tunnels or similar structures and which is adapted to interlock with similar blocks when assembled to provide a solid substantial construction.

20 In the construction of tunnels or similar structures, such as silos, tanks, etc., it is desirable to build same of blocks which have been previously prepared and are capable of 25 being assembled so as to be securely and readily combined or interlocked in such a manner that the wall is in effect a unitary structure having the separate blocks interengaged in such a manner as to be locked 30 against displacement and effectively resist the strain to which the wall is subjected.

It is an object, therefore, of my invention 35 to provide blocks which are adapted to be built up in a structure and having portions overlapping and seated in the adjoining block so as to facilitate assembling and so that when assembled the blocks are thereby held against displacement.

Another object of my invention is to provide 40 blocks adapted to be assembled in a structure and having overlapping tongues at the ends and also overlapping ribs at the sides whereby the blocks are held in position against displacement.

45 Another object of my invention is to provide blocks adapted to be assembled in a structure and having portions of the adjoining blocks overlapped at the ends and sides thereof, and having locking means connecting the overlapped portions of the blocks.

Another object of my invention is to provide 50 a structure comprising similar blocks wherein portions of three adjoining blocks are overlapped and connected by means of a locking member.

Another object of my invention is to pro-

vide a block adapted to be assembled in a structure with portions overlapping and locked to portions of the adjoining block, and having reinforcing means embedded in 60 the block adapted to strengthen the interlocked portions of the block.

Another object of my invention is to provide 65 a connecting means for overlapped portions of adjoining blocks which is adapted to be expanded and thereby locked in position to hold the adjoining blocks together.

Another object of my invention is to provide 70 a structure comprising blocks having flanges engaged in recesses provided therefor in the adjoining blocks, and a reinforcing band in the recesses for holding the blocks in assembled relation.

My invention also has other objects which 75 will be apparent from the following specification and the accompanying drawings, in which I have shown and described my invention in a preferred form.

On the drawings:

Figure 1 is a plan view of the outer side 80 of a wall constructed in accordance with my invention.

Fig. 2 is an enlarged sectional view on the line 2—2 of Fig. 1.

Fig. 3 is a side view of a block embodying 85 my invention.

Fig. 4 is a view of the opposite side of the block shown in Fig. 3.

Fig. 5 is a sectional view on the line 5—5 of Fig. 3. 90

Fig. 6 is an end view of the block looking at the right hand end of Fig. 3.

Fig. 7 is a sectional view on the line 7—7 of Fig. 3.

Fig. 8 is a sectional view on the line 8—8 95 of Fig. 3.

Fig. 9 is a view of the inner face of the block.

Fig. 10 is a detail view partly in section showing the means for securing the locking 100 members in the blocks.

Fig. 11 is a view in elevation showing a tank or silo embodying my invention.

Fig. 12 is an enlarged sectional view on the line 12—12 of Fig. 11. 105

Fig. 13 is a top view of one of the blocks used in the construction of the tank or silo, and shows the reinforcing band applied thereto.

Fig. 14 is an enlarged sectional view on 110 the line 14—14 of Fig. 12 showing the vertical connectors for the blocks.

Fig. 15 is view of the spreader for securing the vertical connectors in the blocks.

As shown on the drawings:

Referring first to Figs. 1 to 10 inclusive, 5 the reference numeral 1 indicates the blocks, each of which is similarly formed and constructed, and which are combined to form the wall. These blocks are particularly adapted for the construction of tunnel walls 10 and similar structures having a curved or circular form, and I have illustrated a block suitable for such purpose, although the invention is not limited to such use. These blocks are made of cement or concrete or 15 otherwise as may be desired and are reversely shouldered at the opposite ends to provide tongues 2 and 3, for effecting a lap-joint connection of the ends of adjoining blocks.

At one side of the block and adjacent the 20 outer face thereof the block is formed with a flange or rib 4, which is adapted to overlap the adjoining block, and the opposite side of the block is recessed as at 5, so as to afford a socket to match and receive the flange 4 25 of the adjoining block. The blocks are all of like construction so that they are interchangeable and when assembled each block has an end portion 3 overlapping an end portion 2 of the adjoining block, and each row 30 of blocks has a continuous flange or offset portion 4, which overlaps and engages in the recess 5, in the adjoining row of blocks. The blocks of the adjoining rows are arranged in staggered relation so that the end 35 joints of the blocks of one row are located intermediate of the end joints of the blocks in the adjoining rows, as is clearly shown in Fig. 1, and the flange or rib 4, is made of a lesser thickness than the projecting portions 2 and 3, so that when assembled in 40 successive rows and in staggered relation the overlapping end portions of the blocks will be overlapped or have the flange or rib 4 of the adjoining row of blocks projecting there- 45 over so that a pin or locking member may be inserted in the overlapping end portions of two adjoining blocks and also in an overlapping portion of a block of the adjoining row, so as to afford a substantial joint to 50 securely hold the blocks together.

For locking the blocks together in the assembled position, each block is provided with a plurality of tubular openings 6, equally spaced apart and along the side of the block 55 which is recessed as at 5, and extending from the recess 5 to the inner face of the block, as shown in Fig. 5, and there are also similar tubular openings 7 and 8, in the projecting end portions 2 and 3 respectively, 60 which, however, are of shorter length than the openings 6, these said openings 7 and 8 being equally spaced from the openings 6 and suitably spaced from the ends of the block so that when the blocks are arranged 65 with the ends overlapping the openings 7

and 8 register and provide a continuous opening of the same length as the openings 6 and spaced from the adjoining openings 6 a distance similar to the spacing of the openings 6 from each other. Thus it will 70 be observed that when the row of blocks are arranged end to end in overlapping relation there are a plurality of equally spaced perforations extending from the inner face of the block to the base of the recess 5, the 75 outer ends of which are adapted to be covered by the overlapping flange or rib 4, of an adjoining row of blocks.

Each block is reinforced by means of the bars or strips 9, 10, 11, 12, 13 and 14, which 80 extend lengthwise of the block and are embedded therein as shown. The strip 10, as shown in Fig. 8, extends between and is looped around the openings 6 and 7 as shown at 15, to reinforce the outer wall of each 85 opening, and the strip 11, which is located adjacent the inner face of the block and parallel therewith is placed in line with the openings 6 and 7 and perforated at each opening to effect a secure engagement of the 90 locking member in the opening as herein-after described.

The strip 14 is arranged in the flange or rib 4 adjacent the outer face of the block and parallel therewith so as to be located 95 directly over the openings 6 and 7, of the adjoining row of blocks in the assembled relation, and there are a plurality of openings 16, which are equally spaced apart and extend outwardly in the rib 4, from the inner 100 face thereof to the strip 14, which openings, when the blocks are assembled as shown in Fig. 1, are adapted to register with the openings 6, and the aligned openings 7 and 8 of the adjoining row of blocks so that locking members which are inserted through the openings 6 and through the aligned openings 7 and 8 extend into the openings 16, for holding the adjoining row of blocks in the proper position. The flange or rib 4, is also 110 provided with a band 13, which is arranged similarly to the band 10, and spaced from the outer edge of the rib and looped around the perforations 16 as at 17, so as to reinforce the walls of the openings 16. 115

For locking the blocks together in assembled relation, I use the tubes 18, which are inserted through the openings 6 and into the openings 16 of the overlapping flange or rib and butt against the inner face of 120 the plate 14. On the inner face of the plate 14, in each opening 16, is a tapered spreader plug 19, which may be polygonal in cross section and is riveted as shown at 20 in Fig. 10, or otherwise secured to the band 14. 125 The tube 18 is inserted from the inside of the wall into the opening 6, and therefrom into the opening 16, until it strikes the tapered plug 19, whereupon it is driven onto said plug 19, so that the walls of the tube 130

are caused to expand as at 21, and the end of the tube is thereby locked securely in the flange 4. After the tube 18 has been driven into position, a plug 22, similar to 5 the plug 19, is inserted in the open end of the tube 18 and forced therein as shown in Fig. 2 so as to expand the end of the tube as at 23, and provide a secure connection of the blocks with the tube. The strap or 10 bar 11 embraces the tube 18, at the point of expansion and is engaged by the tube when expanded and thereby assures a rigid connection.

From the foregoing it will be noted that 15 I have not only provided a block construction in which portions of the block overlap and tend to hold or lock the block in assembled relation, but I have also provided locking means which positively connect the 20 overlapped portions of the blocks so as to securely combine same and prevent displacement or separation of the blocks.

The blocks illustrated in Figs. 1 to 9 are shown as formed for making a tunnel wall, 25 and the numeral 24 indicates a groove with which the inner wall of the blocks may be constructed so as to engage a tunnel frame, and the reference numeral 25 indicates a pocket whereby the blocks may be engaged 30 and supported in the operation of placing the blocks in position.

Referring to Figs. 11 to 15 inclusive, I have shown a modification of my block whereby same is adapted for silo or tank 35 construction. The blocks are formed and provided with the locking openings and connected with tubes 18 in the same manner as the blocks previously described, and in addition are provided with an inner and an 40 outer row of openings 27 and 26 respectively, which extend from side to side of the blocks and are suitably spaced so that when the blocks of the adjoining rows are arranged in staggered relation as shown in Fig. 11, 45 the openings of each row of blocks will register with openings of the adjoining row of blocks so as to admit a locking member for vertically connecting the adjoining rows of blocks.

50 This locking member comprises the tube 28, which is of approximately the same length as the thickness of the block and is adapted to be placed as shown in Fig. 14, so that the ends of the locking member 28 55 are intermediate of the side walls of the block, the said locking members being driven into position and engaged by an expansion member 29, which is flanged intermediate of the ends as at 30 and tapered at each 60 end so as to expand the ends of the tube and cause same to securely bind against the opening of the block and lock the successive rows of blocks together.

As a further means of reinforcing the

tank or silo, a band 31 may be employed 65 and laid in the base of the groove 5 of the block and perforated to admit the tube 18, and the band is covered and inclosed in the assembled structure by the flange or rib 4 of the adjoining row of blocks. 70

While I have shown and described my invention in a preferred form, I am aware that various changes and modifications may be made therein without departing from the principles of my invention, and I therefore 75 do not purpose limiting the patent granted hereon otherwise than necessitated by the prior art.

I claim as my invention:

1. In a sectional structure the combination 80 of a pair of adjoining blocks having overlapped end portions, another block arranged in staggered relation at the side of said pair of blocks and having a portion thereof overlapping the overlapped portions 85 of the pair of blocks, and a locking member connecting the overlapped portions of the pair of blocks and said other block.

2. In a sectional structure the combination 90 of a pair of elongated blocks having overlapped end portions, a similar block arranged in staggered relation at the side of the pair of blocks and having a laterally extending flange seated in a recess in the pair of blocks and overlapping the overlapped 95 portions of the said pair of blocks, and a locking member extending through registering perforations in the overlapped portions of the pair of blocks and the flange of the other block, and means for fastening 100 the locking member in the overlapped portions of the blocks.

3. In a sectional structure, the combination 105 of adjoining blocks having overlapping portions, an apertured reinforcing strip in one of said overlapping portions, a locking member passing through said aperture and connecting the said overlapping portions and means for producing frictional engagement between the walls of said aperture and 110 said member.

4. The combination with a pair of adjoining blocks having overlapping portions, reinforcing strips therein, matching perforations in said overlapping portions and 115 extending through the reinforcing strips, and a locking member in the perforations having the ends thereof expanded to engage the walls of the perforations and the holes in the strips in said overlapping portions.

5. The combination of a circular series 125 of blocks arranged end to end and having offset overlapping ends which interfit, together with offset overlapping ribs along their sides, a groove in the periphery of said circular series of blocks, a reinforcing band embedded in each block and another band

in said groove, an adjoining series of blocks having an annular flange seated in the groove of the other series, and alined vertical holes extending through all of said 5 blocks adapted for the insertion of reinforcing members.

In testimony whereof I have hereunto sub-

scribed by name in the presence of two subscribing witnesses.

CORNELIUS G. HASTINGS.
